MULTIFILAMENT LAMP

John E. Hatula, Painesdale, Mich.

Application December 8, 1939, Serial No. 308,135

4 Claims. (Cl. 176—27)

This invention relates to multiple filament incandescent electric lamps and bases and more particularly to lamps of this kind, wherein the filaments may be selectively connected to the source of electric energy, by rotation of the lamp on its base, to secure various illuminating effects.

One object of this invention is to provide a lamp which may be rotated with reference to its base to select the filament or filaments to be illuminated.

Another object is to provide a lamp base having two insulating members effective to be rotated with reference to each other, constituting a switch to control the circuits to the lamp filaments.

Another object is to provide a lamp base having an electric switch to control each filament of the lamp.

Another object is to provide a lamp base having a plurality of switches, of the same number as the filaments, and means to cause a quick make and break of the electric circuit in the act of selecting the filaments to be illuminated or disconnected.

Another object is to provide an electric lamp having a screw shell base, which may be screwed in a standard socket and in which the amount of illumination can be controlled by rotating the lamp with reference to the base, to a greater or less extent.

Additional objects will appear in the specification and claims, all of which will come within the scope of this invention.

Referring to the drawing:

Fig. 1 is a side view of the lamp and base in section.

Fig. 2 is a top view of the lamp filaments looking at Fig. 1 from the top.

Fig. 3 is a detail as indicated in Fig. 1.

Fig. 4 is a detail as indicated in Fig. 1.

Fig. 5 is a modification.

Fig. 6 is a detail as indicated in Fig. 5.

Similar numerals apply to the same parts throughout the different views.

This invention consists essentially of the illuminating member or lamp and the base upon which it is mounted.

The illuminating member or lamp comprises the glass globe 1 in which are mounted the filaments 2, having their ends connected to lead in wires 3 and 4. The filaments 2 are prevented from sagging or becoming displaced, by supporting wires 5 which hold the filaments 2 at one end thereof and which are secured to a glass support 6 common to all the filaments supporting wires 5.

For the purpose of simplifying the drawing, the filaments in Fig. 1 are shown as occupying 180° of space around the support 6, whereas in practice the filaments are usually arranged to go three quarters of the way or more around the central support 6 as shown in Fig. 2.

The lead wires 3 and 4 are sealed into the glass globe 1 arranged in a single plane in a central inward projection 7 of the same and from there extend to the base of the lamp.

There is a lead wire 4 for each filament 2 and a single lead wire 3 common to all of the filaments 2.

The base 8 with which the lamp is assembled includes a screw shell 9 effective to be screwed into the electric socket with which it is used. Secured within the lower end of the screw shell 9 is an insulating disc 10 which may be cemented or otherwise secured therein, and to facilitate this the disc 10 is provided with a plurality of small longitudinal grooves 11 spaced around its periphery to hold the cement.

Mounted on the upper side of the disc 10 is a ring 11 having a pair of diametrically opposite fingers 12 bent downwardly and crimped in a pair of grooves 13 in the disc 10.

Above the disc 10 and spaced therefrom is a cylindrical terminal support 14, having a groove 15 around its curved side. On one side of the support is a rectangular depression 16 communicating with the groove 15. The terminal support 14 is secured to a tubular shell 17, which is telescoped within the shell 9 and free to rotate therein and is assembled by spinning a bead 18 in the shell 17 to enter the groove 15. A small rectangular portion 28 of the shell 17 is bent inwardly into the depression 16 to prevent the terminal support 14 from turning in the shell 17.

In one half of the terminal support 14 are assembled four spaced terminal eyelets 19, one for each filament 2.

The lead wires 4 are soldered or otherwise electrically connected to the eyelets 19.

In the center of the terminal support 14 is secured a sleeve 20, to the upper end of which is connected the common lead wire 3.

In order to provide means whereby the terminal support 14 and shell 17 can rotate with reference to the disc 10, ring 11 and screw shell 9, a central stud 21 is securely threaded at its upper end into the collar 20 while the lower end of the stud 21 is rotatable in a sleeve 22 secured in the disc 10 and is held in place by a nut 23 screwed on the stud 21 and bearing against a shoulder on

the end of the stud 21 and may be also soldered thereto.

Between the disc 10 and terminal support 14 are mounted four contact springs 24, secured at one end to the ring 11' and which at the other end, bear resiliently against the lower ends of the contact eyelets 19, or against that portion of the lower surface of the support 14 which has no eyelets 19 depending upon the relative position of the terminal support 14 to the disc 10.

The free ends of the contact springs 24 are reflexed as shown in Fig. 1, so that the terminal support 14 may be rotated in either direction with reference thereto.

In order to facilitate the rotation of the lamp, after it has been screwed into a socket, to control the illumination, an insulating ring 25 with a knurled periphery is secured to the shell 17.

The lamp globe 1 may be secured to the shell 17 by cement 26, the shell having a flared end 27 to conform to the shape of the lower part of the globe 1.

In operation, the lamp is rotated upon its base to bring the contacts 24 into electric contact with the filament terminal eyelets 19 and is rotated through 180° in passing from the position when the springs 24 are all bearing against the surface of the terminal support 14, when the lamp is not illuminated, to the position where all of the springs 24 bear against all of the eyelets 19, when the lamp is fully illuminated.

In order to limit the amount of such movement, the shell 17 is provided with a projecting member 33 which comes against a shoulder 34 in the upper edge of the screw shell 9, at the end of each half revolution. One or more filaments 2 may be illuminated at will depending upon the extent the lamp is rotated.

As a modified form of the above embodiment, reference is made to Figures 5 and 6, wherein the spring contacts 24 bear, at their free ends against contacts 28 instead of the eyelets 19 as first disclosed.

The lower surface of the support 14, shown in Fig. 5 is constructed with eight ratchet faces 30, four adjacent faces having the contacts 28 secured thereto, by extension 29 passing through slots 32 and held in place by being bent over at the end on the top of the terminal support 14.

The lead wires 4 in this case pass through openings 31 and may be soldered or otherwise secured to the contacts 28 at one edge thereof.

This modified construction has the advantage of making quick make and break electric contacts when operated. In this case the lamp rotates in one direction only as compared with rotating in both directions, through a half revolution, as in the construction first disclosed.

It is understood, of course, that while this embodiment shows a lamp with four filaments 2, and four sets of switch members 24-19 therefor, yet obviously any number of filaments and a corresponding number of switch members may be used.

It is also understood that the filaments 2 may be all of the same or different candle powers as desired, for example, one filament might be intended to be used as a night light with comparatively low candle power while the remaining filaments could be all alike or different.

While this invention has been disclosed as applying to a multiple filament lamp yet it is not limited thereto as the base could be used with

a single filament to connect or disconnect it with the electric current.

It is readily understood that many changes and deviations might be made in the details of this invention as disclosed, but obviously these would all come within the scope thereof and would not depart from the spirit of this invention.

Having described one method of carrying out my invention, as required by the statutes, so that anyone skilled in the art to which it pertains could make and use the same, what I claim as my invention and wish to secure in Letters Patent is the following:

1. In combination with an incandescent lamp having a plurality of filaments, of a base for the lamp, including a straight metal tube secured at one end to the lamp, a disc of insulating material secured to the other end of the tube, filament terminals assembled to said disc, a screw shell, effective to be inserted in an electric socket, having a straight tubular end, telescoped over the first named tube, forming a bearing for the latter to be journaled therein, a second disc with insulating material, assembled to the bottom of the screw shell, and a plurality of resilient contacts secured to the second disc, one for each filament and effective to contact the filament terminals when the lamp is rotated.

2. In combination with an incandescent lamp, having a plurality of filaments, of a base for the lamp, including a straight metal tube secured at one end to the lamp, a disc of insulating material secured to the other end of the tube, filament terminals assembled to said disc, a screw shell, effective to be inserted in an electric socket, having a straight tubular end, telescoped over the first named tube, forming a bearing upon which the latter is journaled, a second disc of insulating material, assembled to the bottom of the screw shell, a plurality of resilient contacts, effective to contact the filament terminals when the lamp is rotated and an annular metal member, having fingers extending from the periphery thereof, secured to the second disc by said fingers, and to which annular metal member resilient contacts are secured.

3. A base for an electric lamp, including a straight metal tube, secured at one end directly to the lamp, a pair of switch members rotatable and coacting to control current to the lamp, one member, including a disc of insulating material, secured to the opposite end of the tube, and electric contacts assembled to said disc, connected to the lamp, a screw shell having a straight tube at one end telescoped with the first named tube, upon which it is free to rotate, the other switch member including a disc of insulating material secured to the screw shell and electric contacts mounted on the disc and connected thereto effective to engage the first named contacts, and means to retain both tubes in assembled rotatable juxtaposition.

4. A base for an electric lamp, including a straight metal tube, secured at one end to the lamp, a screw shell having a straight tube at one end, telescoped with and journaled upon the first named tube at the opposite end thereof from the lamp, a pair of switch members, effective to rotate with reference to each other to control current to the lamp, one member secured to the first named tube and the other member secured to the screw shell, and means connecting said members at their center to retain the tubes in assembled rotatable longitudinal relation.

JOHN E. HATULA.
